FIG. 4

UNITED STATES PATENT OFFICE

2,587,150

HANGING SUPPORT

Donald A. Hansen, Robbinsdale, and Cameron R. Lyseng, Minneapolis, Minn.

Application October 16, 1948, Serial No. 54,944

3 Claims. (Cl. 248—58)

1

Our invention relates to improvements in hanging supports, an object thereof being to provide a simple, durable and relatively inexpensive article of such nature, particularly though not exclusively for supporting clothes lines, the same being adapted to be quickly, easily and securely attached to and removed from exposed overhead joists such as those customarily found in the basements or other unfinished areas of dwellings.

More specifically, it is an object of our invention to provide a hanging support of the instant nature comprising a hanger-bar and a clamp-bar adjustably tied thereto, whereby hanger-bar and clamp-bar may be caused to engage the opposite sides of a joist in jaw-like manner and securely grip such joist between them.

Another object of the invention is to provide a hanging support of the present character including a pair of hanger-bars with companion clamp-bars and an article-attaching rail secured to the hanger-bars in which such support the clamp bars may be alterably tied to the hanger-bars to enable the support to be hung from a single joist or from two spaced joists.

Other objects of the invention reside in the novel combination and arrangement of parts and in the details of construction hereinafter illustrated and/or described.

In the accompanying drawing, Fig. 1 is a perspective view of a support embodying our invention and shown as hung from a single overhead joist; Fig. 2 is a perspective view of the hanging support shown in Fig. 1, but with the parts thereof assembled for the attachment of the support to two spaced overhead joists; Fig. 3 is a perspective view in detail of a clamp-bar used in association with a companion hanger-bar, and Fig. 4 is a plan view of a hook which is applicable to the support for the attachment of an article thereto.

Reference being had to the accompanying drawing, it will be seen that Figs. 1 and 2 show exposed overhead joists 10 such as those customarily found in conventional building construction.

The illustrated form of our improved support includes a pair of hanger-bars A of angle iron and a rail B of angle iron to which the lower ends of said hanger-bars A are rigidly secured. The fastening of the rail A to the hanger-bars B may be accomplished in any suitable manner, as by welding or otherwise, it being preferable that one of the flanges of the rail B, as at 11, stand upright. In fastening the hanger-bars A to the rail B, said hanger-bars are relatively disposed in

2

"right" and "left" relationship so that the flanges 12 thereof will occupy relatively remote disposition in a common plane, while the flanges 13 thereof will occupy relatively proximate disposition in parallel planes spaced apart a distance equal to the measurement between the opposite faces of adjacent joists 10. Each of the flanges 12, 13 of each hanger-bar A is formed therealong intermediately thereof with a number of bolt holes 14.

10 A pair of clamp-bars C of angle iron are supplied for cooperation with the hanger-bars A. These clamp-bars C are of "right" and "left" pattern. The flange 15 of each clamp-bar C is formed intermediately thereof with a bolt hole 16 therein, the lower terminal portion of such flange 15 being bent inwardly at right angles to the main portion thereof to provide a toe 17 for fulcruming engagement with one or the other of the flanges 12, 13 of one of the hanger bars A when said main portion of the flange 15 of the clamp-bar C is disposed to confront the upper portion of such hanger-bar flange. To facilitate the bending of the flange 15 of a clamp-bar C, 20 the other flange 18 of such bar is triangularly notched, the apex of the notch registering with the line-of-bend in the flange 15 of said clamp-bar C.

25 A pair of headed bolts 19 are supplied, each thereof being threadedly fitted opposite its head with a binding nut 20. One of the bolts 19 serves to tie one clamp-bar C to one hanger-bar A and the other bolt 19 serves to tie the other clamp-bar C to the other hanger-bar A. In each case, the bolt 19 will extend through the hole 16 in the flange 15 of the clamp-bar C and through one of the holes 14 in one of the flanges 12, 13 of the hanger-bar A with the head of the bolt 19 engaging the outer face of one of the flanges 30 through which the bolt extends and the binding nut 20 on the bolt 19 engaging the outer face of the other of said flanges.

35 To suspend the support from a single joist, as shown in Fig. 1, the tie-bolts 19 are extended 40 through corresponding bolt-holes 14 in the flanges 12 of the hanger-bars A and through the bolt-holes 16 of the respective clamp-bars C selected for association with the respective hanger-bars A. The particular clamp-bar C selected for association with each hanger-bar A is the one whose flange 18 will lie in the plane of the flange 13 of the hanger-bar A when said clamp-bar C is positioned relative to the hanger-bar A with the toe portion 17 of its flange 15 fulcrumed 45 against said flange 12 and with the main portion 50

of its said flange 15 confronting said flange 12 of said hanger-bar A (Fig. 1). With the clamp-bars C tied to the hanger-bars A by the bolts 19, the assembly is applied to a joist 10 with the upper portions of the flanges 12 of the hanger-bars A confronting one face of the joist 10 and with the upper portions of the flanges 15 of the clamp-bars C confronting the other face of said joist. Thereupon, the binding nuts 20 on the bolts 19 will be tightened with the result that the upper portions of the clamp-bars C will be drawn toward the hanger-bars A and thereby cause said clamp-bars C and hanger-bars A to grip the joist firmly in jaw-like manner. From the foregoing it will be obvious that detachment of the support from the joist 10 may be readily effected simply by loosening the binding nuts 20 on the tie-bolts 19.

To suspend the support from two adjacent joists, as shown in Fig. 2, the tie-bolts 19 are extended through corresponding bolt holes 14 in the flanges 13 of the hanger-bars A and through the bolt holes 16 of the respective clamp-bars C selected for association with the respective hanger-bars A. In this case, the particular clamp-bar C selected for association with each hanger-bar A is the one whose flange 18 will lie in the plane of the flange 12 of the hanger-bar when said clamp-bar is positioned relative to the hanger-bar with the toe portion 17 of its flange fulcrumed against said flange 13 and with the main portion of its said flange 15 confronting said flange 13 of said hanger-bar (Fig. 2).

To enable the tie-bolts 19 to underlie closely the lower edge or edges of a joist or joists to which the support is attached and at the same time enable the rail B to be positioned at various elevations, we provide said series of holes 14 in the flanges 12, 13 of the hanger-bars A for said tie-bolts 19. Obviously, the higher the holes 14 may be, which receive the tie bolts 19, the lower will be the position assumed by the rail B.

Lines or other articles to be supported may be secured directly to the rail B or hanger bars A in any suitable manner. As shown, apertures 21 formed in the upstanding flange 11 of the rail B facilitate the attachment of articles to said rail and such apertures 21 also provide for the ready attachment to said rail B of hooks D constructed as shown in Fig. 4. This form of hook has a hooked head 22, shank 23 and a butt-stop 24 formed by making a return bend in the terminal portion of the shank 23, said form of hook being readily threaded into a rail-aperture 21 hooked-head foremost.

In an alternate form of the invention, one or more of the hanger-bars A, with associated clamp-bar or clamp-bars C, will be employed without an article attaching member such as the rail B. In such case, each of the flanges 12, 13 of each hanger-bar A will be formed near the lower end thereof with an aperture 25 adapted to receive a line or other article to be supported and adapted further to admit of the application thereto of an attaching hook of suitable construction such, for example, as that shown in Fig. 4.

Changes in the specific form of our invention as herein described, may be made within the scope of what is claimed without departing from the spirit of our invention.

Having described our invention, what we claim as new and desire to protect by Letters Patent is:

1. In a hanging support for attachment to an overhead structural member, a hanger-bar of angle iron, a clamp-bar of angle iron, one flange

of said hanger-bar being formed intermediately thereof with a bolt hole, said clamp-bar being adapted to be disposed alongside said hanger-bar with one of its flanges mated with and confronting said last mentioned flange of said hanger-bar and with the other of its flanges disposed in the plane of the other flange of said hanger-bar, said confronting flange of the clamp-bar having a bolt hole therein intermediately of the clamp-bar and having its lower portion angularly bent to form a toe for fulcruming engagement with the confronted flange of the hanger-bar, a tie-bolt loosely received in the bolt hole in the confronting flange of said clamp-bar and extending therethrough and through the bolt hole in the confronted flange of said hanger-bar, said tie-bolt operating upon being tightened to tilt the clamp-bar and bring the upper portion of said confronting flange thereof toward the upper portion of said confronted flange of the hanger-bar to engage said portions of said flanges of clamp-bar and hanger-bar in jaw-like manner with the opposite sides of said structural member.

2. In a hanging support for attachment to an overhead structural member, a hanger-bar of angle iron having means for the attachment of an article thereto at the lower portion thereof, a clamp-bar of angle iron adapted to be disposed alongside said hanger-bar with one of its flanges mated with and confronting one of the flanges of said hanger-bar and with the other of its flanges disposed in the plane of the other flange of said hanger-bar, said clamp-bar having its lower portion angularly bent to form a toe for fulcruming engagement with the confronted flange of the hanger-bar, adjustable tie means interposed between intermediate portions of the confronting flange of said clamp-bar and the confronted flange of said hanger-bar, said tie means operating to tilt the clamp-bar and bring the upper portion of said confronting flange thereof toward the upper portion of said confronted flange of the hanger-bar to engage said portions of said flanges of clamp-bar and hanger-bar in jaw-like manner with the opposite sides of said structural member.

3. In a hanging support, a pair of hanger-bars of angle iron relatively disposed with one flange of one hanger-bar coplanar with one flange of the other hanger-bar and with the second flanges of said hanger-bars occupying parallel planes, each flange of each hanger-bar being formed intermediately thereof with a bolt hole, a rail for the attachment thereto of an article or articles to be supported, said rail being secured to the lower ends of said hanger-bars tying them together with said second flanges thereof spaced apart for face-to-face engagement with spaced joists of a building, a pair of clamp-bars of angle iron, each clamp-bar being adapted to be disposed alongside one or the other of the hanger-bars with one of its flanges mated with and confronting a selected one of the two flanges of such hanger-bar and with the other of its flanges disposed in the plane of the other flange of such hanger-bar, said confronting flange of the clamp-bar having a bolt hole therein intermediately thereof and having its lower portion angularly bent to form a toe for fulcruming engagement with the confronted flange of the hanger-bar, a tie-bolt for each clamp-bar loosely received in the bolt-hole therein and extending therethrough and through the bolt hole in the flange of the companion hanger-bar confronted by the clamp-bar, said tie-bolt operating upon being tightened

to tilt the clamp-bar and bring the upper portion thereof toward the upper portion of said hanger-bar, the upper portions of the coplanar flanges of the hanger-bars and the clamp-bars, when mated therewith, being adapted to engage in jaw-like manner the opposite sides of a single joist, the upper portions of the spaced parallel flanges of said hanger-bars and the clamp-bars, when mated therewith, being adapted to engage in jaw-like manner the opposite sides of spaced joists.
